UNITED STATES PATENT OFFICE.

WILLIAM BERRENBERG, OF BOSTON, MASSACHUSETTS.

ROTARY ENGINE.

SPECIFICATION forming part of Letters Patent No. 351,957, dated November 2, 1886.

Application filed March 24, 1886. Serial No. 196,315. (No model.)

To all whom it may concern:

Be it known that I, WILLIAM BERRENBERG, of Boston, in the county of Suffolk, State of Massachusetts, have invented certain new and 5 useful Improvements in Rotary Engines, of which the following is a specification.

This invention relates to an improved rotary steam-engine that is worked with expansion of steam by a simple valve-motion, and that 10 can be run at high speed, so as to be applicable for lathes, circular saws, &c., and similar purposes.

The invention consists of a casing or shell 15 formed of intersecting cylinders, which are arranged sidewise of each other, one cylinder containing a rotary valve, while the other cylinder contains a rotary piston of the same diameter as the rotary valve, said piston being provided at diametrically-opposite points with 20 fixed abutments having hinged wings. The abutments and wings fit into corresponding recesses of the rotary valve, the recesses being connected by a diametrical steam-channel, through which the steam is supplied to the 25 piston of the main cylinder.

In the accompanying drawings, Figure 1 represents a vertical transverse section of my improved rotary steam-engine, taken on line *xx*, Fig. 2. Fig. 2 is a vertical longitudinal 30 section through the main cylinder on line *yy*, Fig. 1; and Fig. 3 is a plan of the engine.

Similar letters of reference indicate corresponding parts.

Referring to the drawings, A represents the 35 casing or shell of my improved rotary steam-engine, which casing is supported on a bed-plate, B, and formed of two intersecting cylinders—a larger one, A', for the steam-piston D, and a smaller one, A², for the rotary valve E.

The casing A is closed at the sides by heads 40 A³, which are provided with stuffing-boxes for the driving-shaft C. The driving shaft C turns in bearings C' at opposite sides of the casing A. A gear-wheel, b, on the driving-shaft C, 45 meshes with a gear-wheel, d, of the same size on the shaft E' of the rotary valve E, so that the same is rotated at the same speed as the piston D. The piston D is provided with fixed abutments D' at diametrically-opposite points, 50 which abutments are provided with segmental

wings D², that are hinged at one end to the abutments D', as shown in Fig. 1. The wings D² are beveled at their under side and at the side opposite the wings' connection with the abutments D', so as to facilitate the entering 55 of the steam between the abutments and wings, and force the latter in outward direction into tight contact with the interior surface of the main cylinder A'. The abutments D' and wings D² project beyond the circumference of 50 the piston D, and fit into recesses e² at diametrically-opposite points of the rotary valve E, said recesses being connected by a diametrical channel, e'.

The live steam enters through an inlet-port, 65 f, of the valve-chest A², that is arranged at right angles to a horizontal plane passing through the axes of the shafts C and E, and passes through the center channel, e', when one of the recesses e is moving across the inlet-port f. The live steam acts then on the abutment D' and hinged wing D², and imparts rotary motion to the piston until the steam is shut off as the recess e arrives at the abutment g, formed at the intersection of the cylinders A' A², as shown in Fig. 1. In this position the steam works expansively on the wing D² of the piston until said wing arrives at the exhaust-port f' of the casing, which exhaust-port is located in line with the axes of 70 the shafts C E'. A recess, g', at the lower part of the steam-chest A², serves for permitting the steam to pass to the main cylinder A' until the steam is shut off. This recess g' is necessary, as otherwise the lower part of the steam-chest would shut off the steam. The intermediate positions of the rotary valve E and piston D are shown in dotted lines in Fig. 1, and illustrate the position of the valve and piston at the moment when the expansive action of the steam commences. As soon as one abutment D' of the piston has passed the exhaust-port, the other is in a position to be 75 acted upon again by the live steam, and so on, whereby continuous rotary motion is imparted 90 to the piston D and driving-shaft C. The steam entering between the abutments and the hinged wings presses the latter tightly against the inner surface of the steam-cylinder, and 95 keeps thereby the wings steam-packed with- 100

out requiring any other packing. By the gradual wear at the outer side of the wings the outward motion of the same increases until the wings are entirely worn off, when they are 5 replaced by detaching their hinge pintles from the abutments and replacing them with new wings.

The sides of the rotary valve and piston are tightly packed by a suitable metallic or other 10 packing at one side of the same, or in any other approved manner.

My improved rotary steam-engine is of simple construction, can be readily kept tight, and can be run at high speed, so as to be specially 15 adapted for machines in which high speed is required.

Having thus described my invention, I claim as new and desire to secure by Letters Patent—

1. The combination of a casing consisting 20 of intersecting cylinders, a piston located in the main cylinder, abutments at diametrical points of the piston, segmental wings hinged to said abutments, a rotary valve having the same diameter as the piston, and provided with 25 recesses at diametrically-opposite points fitting on the abutments and wings, and a diametrical steam-channel connecting said recesses, substantially as set forth.

2. The combination of a casing consisting 30 of a larger main cylinder and a smaller steam-

chest, and having an inlet-port and an exhaust-port, a piston located in the main cylinder, abutments at diametrical points of the piston, segmental wings hinged to said abutments, a rotary valve of the same size as the piston 35 located in the valve-chest and provided with recesses corresponding to the projecting abutments and wings, a diametrical channel connecting the recesses of the slide-valve, and gearing by which rotary motion is transmitted 40 from the main shaft to the shaft of the rotary valve, substantially as set forth.

3. The combination of a casing formed of a main cylinder and a smaller steam-chest, said steam-chest having a segmental recess at the 45 lower part, a piston located in the main cylinder, abutments at diametrical points of the piston, segmental wings hinged to the abutments and provided with beveled under sides, a rotary valve in the steam-chest, having recesses fitting over the abutments and wings, 50 a steam supply channel connecting said recesses, substantially as set forth.

In testimony that I claim the foregoing as my invention I have signed my name in presence of two subscribing witnesses.

WILLIAM BERRENBERG.
